ANGLE BLOCK FOR CYLINDER BORING MACHINES

Charles O. Boston, East Boone Township, Bates County,
Mo. (R.R. 1, Drexel, Mo.)

Filed Mar. 28, 1963, Ser. No. 74,172

Term of patent 14 years

(Cl. D55—1)

FIG. 1

FIG. 2

FIG. 4

FIG. 3

FIG. 5

FIGURE 1 is a perspective view of an angle block for cylinder boring machines, showing my new design.

FIGURES 2 and 3 are, respectively, bottom plan and end elevational views thereof.

FIGURES 4 and 5 are, respectively, side elevational and top plan views thereof.

I claim:

The ornamental design for an angle block for cylinder boring machines, substantially as shown.
